United States Patent Office.

WILLIAM H. JOECKEL, OF NEW YORK, N. Y.

Design No. 4,690, dated February 28, 1871.

DESIGN FOR A SCHOOL-SEAT.

The Schedule referred to in these Letters Patent and making part of the same.

To all whom it may concern:

Be it known that I, WILLIAM H. JOECKEL, of the city of New York, in the county and State of New York, have invented a new and original Design for a School-Seat or Bench; and I do hereby declare that the following is a full, clear, and exact description thereof, which will enable others skilled in the art to make and use the same, reference being had to the accompanying photographic illustrations forming part of this specification.

The photographs represent a perspective view of my new design for a school-seat or bench.

This invention relates to a new configuration of the legs or standards, and also to a new shape of back-support of a school-seat or bench.

The legs or standards A A are made symmetrical, that is, of equal form in front and rear, approaching in their complete outline that of a lyre, as shown.

The braces a a in the upper part of each standard may be varied in form or omitted, my invention relating more particularly to the outline of the standard proper.

The side pieces B B, which extend above the seat C, for the support of the back D, are made in shape of a bat, that is to say, they run almost to a point at the upper end, and are enlarged and rounded at the lower end, as shown.

They may be solid or of open-work, and have in the latter case suitable inner braces b.

I claim as my invention—

1. The design for the legs or standards of a school-seat or bench, as shown.
2. The design for the side pieces or back-support of a school-seat or bench, as shown.

The above specification of my invention signed by me this 1st day of February, 1871.

WM. H. JOECKEL.
